UNITED STATES PATENT OFFICE.

JOSEPH G. KAEMPFER, OF NEW YORK, N. Y.

DESIGN FOR A STATUE DOLL.

61,139.

Specification for Design. Patented June 27, 1922.

Application filed February 7, 1920. Serial No. 357,106. Term of patent 3½ years.

To all whom it may concern:

Be it known that I, JOSEPH G. KAEMPFER, a citizen of the United States, residing in the city of New York, county and State of New York, have invented a new, original, and ornamental Design for a Statue Doll, of which the following is a specification, reference being had to the accompanying drawing, forming a part thereof.

In the drawing,—

I claim:

The ornamental design for a statue doll, substantially as shown.

This specification signed this 6th day of February, 1920.

JOSEPH G. KAEMPFER.
